(57) **CLAIM**

The ornamental design for the container sidewall having grips, as shown and described.

DESCRIPTION

FIG. 1 is a left side elevational view of the container sidewall having grips of my new design, the right side elevational view being a mirror image thereof;

FIG. 2 is a rear elevational view thereof;

FIG. 3 is a front elevational view thereof;

FIG. 4 is a top plan view thereof; and,

FIG. 5 is a bottom plan view thereof.

The broken line showing of the upper and lower portions of the container in FIGS. 1-5 is for illustrative purposes only and forms no part of the claimed design.
